United States Patent Office

Des. 193,140
Patented July 3, 1962

193,140

SURGICAL CLIP

Adolph M. Brown, 9735 Wilshire Blvd.,
Beverly Hills, Calif.

Filed Oct. 9, 1959, Ser. No. 57,877

Term of patent 14 years

(Cl. D17—3)

FIG. 1

FIG. 2

FIG. 3

FIG. 1 is an enlarged perspective view of a surgical clip showing my new design;

FIG. 2 is a bottom plan view thereof turned 90 degrees; and

FIG. 3 is a front elevational view thereof in actual size.

I claim:

The ornamental design for a surgical clip, as shown.
